LOCKING DEVICE FOR THROTTLE VALVES

Raymond H. Smickle, Belvidere, N. J., assignor
to Ingersoll-Rand Company, New York, N. Y.,
a corporation of New Jersey

Application June 28, 1940, Serial No. 342,846

1 Claim. (Cl. 251—164)

This invention relates to throttle valves, and more particularly to a locking device for throttle valves of the rotary type used for controlling the admission of pressure fluid into rock drills and similar machines.

The invention is intended more particularly for use on rock drills of the hand-held type. These tools and their accessories are handled by the operator without assistance and, being of considerable weight, are usually moved from one drilling site to another by dragging them along the ground. In thus moving a tool about numerous injuries to operators have been caused when the throttle valve controlling the admission of pressure fluid into the rock drill was accidentally opened, by projections on the ground, and the drill thereby set in operation. In such event the working implement may be violently ejected from the rock drill and the rotation mechanism may cause a rapid rotary movement of the casting of the rock drill and cause severe injury to the hand grasping it.

It is accordingly an object of the invention to preclude the possibility of accidentally setting the rock drill in operation.

Another object is to enable the throttle valve controlling the admission of pressure fluid in the rock drill to be conveniently locked in position.

Other objects will be in part obvious and in part pointed out hereinafter.

In the drawing accompanying this specification and in which similar reference numerals refer to similar parts,

Figure 1 is an elevation, partly in section, of a throttle valve assembly equipped with a locking device constructed in accordance with the practice of the invention and showing the locking elements in the locking positions,

Figure 2 is a plan view of the assembly.

Figure 3 is a transverse view taken through Figure 1 on the line 3—3, and

Figure 4 is a view similar to Figure 1 showing the locking elements in releasing positions.

Referring more particularly to the drawing, 20 designates a valve chest having a bore 21 to accommodate a throttle valve 22, a stem 23 of which projects from the bore 21 and carries a handle 24 whereby the throttle valve may be rotated.

The valve chest 20 is shown as being in the form of a coupling member having a passage 25 extending entirely therethrough and controlled by the throttle valve 22, the latter having a transverse port 26 to afford communication between the portions of the passage 25 ly-

ing on the opposite sides of the bore 21. The ends of the valve chest are externally threaded so that one end may be attached to a rock drill (not shown) and the other end to a conduit 5 serving to convey pressure fluid from a source of supply to the valve chest.

The large end of the bore 21 is sealed by a plug 27 threaded into the valve chest, and on the opposite side of the valve chest is a boss 28 that encircles the bore 21 and has diametrically opposed notches 29 and 30 in its periphery.

The handle 24 comprises a grip portion 31 that extends radially of the stem 23 and a hub 32 having an aperture 33 to receive the stem 23. A pin 34 extending through the hub 32 and the stem 23 secures the handle 24 to the throttle valve.

In the opposite sides of the handle 24 are slots 35 and 36 that extend throughout the length of 20 the handle and through the opposite sides of the hub 32 to accommodate levers 37 and 38, respectively. Each lever is of L-shape and carries a flange 39 suitably curved on its outer side to present a convenient gripping surface. The 25 opposite ends of the levers are secured pivotally to the hub 32 by pins 40 seated in the hub 32 and extending through the levers. On one side of the pins 40 are arms 41 of the levers to engage the notches 29 and 30 in the closed position of 30 the throttle valve 22.

To the end that the arms 41 may be held firmly in engagement with the notches in the boss 28 unaffected by the vibration incident to the operation of the rock drill to which the throttle valve 35 may be attached, the levers 37 and 38 are provided, respectively, with opposed seating surfaces 42 and 43 that lie on the sides of the pins 40 opposite the arms 41. The seating surfaces 42 and 43 lie on diametrically opposite sides of the hub 40 32, and in the portion of the hub lying between the seating surfaces is a bore 44 to receive plungers 45 that extend from opposite ends of the bore 44 to abut the seating surfaces. The plungers have cavities 46 in their opposed ends to receive a spring 47 serving to urge the levers toward the locking positions.

The operation of the device is as follows: Whenever it is intended to rotate the throttle valve 22, say, from the closed position illustrated 50 in Figure 1, the levers 37 and 38 are tripped by pressure applied to the flanges 39 for moving the arms 41 out of the notches 29 and 30. The throttle valve may then be rotated a partial revolution to carry the arms 41 onto the side of 55 the boss, between the notches 29 and 30, to es-

tablish a desired degree of communication of the port 26 with the passage 25. The throttle valve will be held in this position by the frictional engagement between its tapered surface and that of the bore 21 and when it is desired to cut-off the flow of pressure fluid the throttle valve is rotated in either a right or left hand direction until the arms 41 coincide with the notches. The spring-pressed plungers will then actuate the levers to move the arms 41 into the notches for holding the throttle valve immovable.

As will be readily apparent, the throttle valve may be conveniently rotated in either a right hand or a left hand direction for opening and closing it. This is highly desirable in devices of this character for the reason that it becomes necessary, at times, to cut-off the pressure fluid supply to the rock drill quickly in situations where serious damage or injury might result if the matter of the direction in which the throttle valve should be rotated must first be considered.

Another highly desirable advantage of the present invention is that the throttle valve will be securely locked in position so that when its handle engages a protuberance on the working surface there will be little or no danger of the valve being inadvertently opened.

If, as may happen upon occasion, one of the levers is accidentally tripped out of locking position, the other lever will remain in engagement with the boss 28 and with one of the levers in the disengaged position, the spring 47 will be additionally compressed and in this way the other lever will be pressed firmly into locking engagement.

I claim:

10 A locking device for throttle valves, comprising a casing having a bore and notches on diametrically opposite sides of the bore, a rotary throttle valve in the bore, a handle for the throttle valve comprising a hub and a grip portion extending laterally of the hub, said handle having slots in the opposite sides thereof extending along the hub and the grip portion, levers in the slots, pins for pivotally securing the levers to the handle, latch portions on the levers lying on one 15 side of the pins to engage the notches, seating surfaces on the levers opposed to each other and lying on the opposite side of the pins, plungers abutting the seating surfaces, and a spring interposed between the plungers to maintain the latch portions in engagement with the notches.

RAYMOND H. SMICKLE.
